ATTORNEY

UNITED STATES PATENT OFFICE

FREDERICK GEORGE CREED, OF CROYDON, ENGLAND, ASSIGNOR TO CREED AND COMPANY, LIMITED, OF CROYDON, ENGLAND

PRINTING WHEEL

Application filed February 14, 1929, Serial No. 339,871, and in Great Britain February 14, 1928.

This invention relates to a printing wheel for type printing telegraph and analogous uses, and has for its object to produce a type wheel which shall be light in construction and therefore capable of being driven at a high speed without damage, but which shall at the same time ensure correct alignment and clean sharp printing of the printed characters. It has also for its object to support the printing wheel in a better manner than previously upon its shaft and to improve the frictional driving means between it and the driving shaft.

For this purpose the type characters are carried separately on holders arranged around the wheel and mounted to slide endways to print a character.

Figure 1 of the accompanying drawings shows in longitudinal section one construction of printing wheel and associated parts in accordance with this invention; Figure 2 shows a longitudinal section of the wheel itself, and Figure 3 is an edge view of a type bar.

The type bars 7 are carried in aligned slots in discs 2a and 3a. The printing wheel comprising a hub 22 provided with flanges 23 and 24. The flange 24 is formed with a forwardly projecting portion 24a, and the discs 2a and 3a are secured to this portion. In the embodiment illustrated the discs 2a and 3a are constituted by a ring of channel section secured to the portion 24a. The rear support for the bars 7 is constituted by a collar 25 of angle section carried by the flange 24 of the hub 22 and bearing at its rear side against an outwardly extending portion 24b of the flange 24, the collar 25 also acting to position the discs 2a and 3a.

The type bars 7 are normally held in their rear position against the ring 25 by a front retaining ring 4a that bears against recessed portions 7b of the bars. Horizontally arranged coiled springs 8a are secured to the ring or disc 4a and to the rear flange 23 of the hub 22, extending through holes 24c in the flange 24, and serve to return to normal position any type bar that has been struck forward by a printing hammer 9 or the like.

A radial arm 26 is secured to the flange 23 of

the hub 22 and is formed by pressing a sheet metal blank into shape.

The face of each type character may be curved or flat shape to suit the surface of the platen used for supporting a tape or sheet of paper on which the impression is to be made.

The hub 22 is mounted on the end portion 14a of its driving shaft 14 on which it is held by a plate 15 that bears against the outer end of the hub 22 and is fixed to the free end of the shaft by a screw 16. The arrangement is such that when the plate 15 is removed the hub 22 carrying the type bars 7 can be readily slipped off the shaft 14.

Fixed to the driving shaft 14, near the inner end of the hub 22, is a cup-shaped head 17 open at its front side and across which extends the radial arm 26 fixed to the hub 22. Fitting tightly against the inner periphery of the rim of the cup-shaped head 17 is a friction ring 19 provided with an inturned end portion engaged by a second lateral extension 26b of the radial arm 26. Normally the friction ring 19 makes driving connection with the rim of the head 17 and rotates the radial arm hub and printing wheel. Selector bars 18 are provided one of which is selected in known manner to be released and drop into the path of the extension 26a of the arm 26 to stop the type wheel. The portion of the driving shaft adjacent to the inner side of the head 17 is mounted to rotate in a ball bearing 20 carried by the adjacent end of a stationary cylinder 21 used for carrying adjustable annular combs used for the selective release of the bars 18.

Claims.

1. A printing device comprising a constantly rotating shaft, a typewheel journaled on said shaft, a clutch connection between said shaft and wheel, a plurality of character carrying members on said wheel and means for causing longitudinal movement of said members.

2. A printing device comprising a continuously rotating shaft, a typewheel journaled on said shaft, a clutch connection between the shaft and the wheel, a plurality of character carrying members and supporting and guiding means in which said mem-

bers may be moved in the direction of their length.

3. A printing device comprising a continuously rotating shaft, a typewheel journaled on said shaft, a clutch connection between said shaft and wheel, a plurality of character carrying members, supporting and guiding means in which said members may be moved in the direction of their length and parallel to said shaft to effect printing.

4. A printing device comprising a constantly rotating shaft, a typewheel journaled on said shaft, a clutch between the shaft and the wheel, a plurality of character carrying members, supporting and guiding means in which said members may be moved longitudinally and restoring means common to all of said members.

5. A printing device comprising a constantly rotating shaft, a typewheel journaled on said shaft, a clutch between the shaft and the wheel, a plurality of character carrying members, supporting and guiding means in which said members may be moved longitudinally, a single screw being the sole means for retaining said wheel and clutch on said shaft.

In witness whereof, I hereunto subscribe my name this 31st day of January, 1929.

FREDERICK GEORGE CREED.
